UNITED STATES PATENT OFFICE

WILLIAM A. DILLON, OF SANTA CLARA, CALIFORNIA

LATHER BRUSH

Application filed June 13, 1931. Serial No. 544,068.

This invention relates to lather or what are known as fountain brushes, and particularly to a brush of this general character used in connection with shaving. Various types of such brushes have been designed and tried out, one example being shown in the patent of myself and C. W. Weingand No. 1,762,616 dated June 10, 1930; but as far as I am aware all these prior brushes feed the cream into the center of the brush at the base of the bristles. With such an arrangement however there is a great waste of the cream, since it is not transferred onto the face until it has reached the outer end of the bristles, while the amount of cream actually dispensed and which if not used must be cleaned out when the brush is washed, is much greater than that necessary for a single shave. There is also of course the possibility that if the brush is not thoroughly cleaned a certain amount of cream at the base of the bristles will harden and cake.

The principal object of my present invention is to avoid this objectionable feature by arranging for the dispensing of the cream directly to the outside of the bristle area; and to provide an element to receive the cream thus dispensed so arranged that the cream may be directly transferred to the face in an easy and convenient manner.

A further object of the invention is to provide a brush of this general character in which the bristles are removably mounted as a unit from the body or handle portion so that said bristles may be replaced without having to purchase an entire brush. As a further object I have provided a handle member which may be removably applied to the body of the brush instead of the cream holding tube if desired, so that the brush can be used in the same manner as an ordinary brush.

These objects I accomplish by means of such structure and relative arrangement of parts as will fully appear by a perusal of the following specification and claims.

In the drawings similar characters of reference indicate corresponding parts in the several views:

Fig. 1 is a perspective view of my improved

brush. Fig. 2 is a sectional elevation of the same. Fig. 3 is a perspective view of the bristle unit detached. Fig. 4 is a top plan view of the body of the brush with the bristle unit removed. Fig. 5 is a perspective view of the flexible flap detached. Fig. 6 is a cross section of the body taken on the line 6—6 of Fig. 2. Fig. 7 is a top plan view of the cream tube. Fig. 8 is a fragmentary perspective view of the tube. Fig. 9 is a perspective outline of the brush showing the detachable handle member engaged therewith.

According to the numerals on the drawings 1 denotes the body of the brush of substantially conventional shape, which is provided at its lower end with a bore 2 which terminates at the bottom in an outwardly flaring portion 3. A conduit 4 extends upwardly from the bore and at its upper end leads to an outlet in one side of a cylinder 5 which is mounted lengthwise in the body toward one side of the same and extends to the top thereof. A spring pressed plunger 6 in the cylinder normally covers the outlet of the conduit. Said plunger is connected below the cylinder to a finger trigger 7 which is movable in a verticle slot 8 in the body. The top of the cylinder is inwardly leveled as shown to form a sealing seat with the adjacent end of the plunger, to prevent possible leakage of air past the plunger and drying out of the cream at the conduit outlet.

Formed in the top of the body is a socket 9 disposed to one side of the cylinder, the edge A of the socket adjacent the cylinder being of relatively great curvature as shown. Shaped to removably fit in the socket is a base member 10 in which the bristles 11 are mounted in the usual way. The edge of the base member which is symmetrical to the edge A of the socket is spaced sufficiently therefrom to receive the lower edge of a flap 12 therein. This flap is preferably of smooth flexible rubber, narrowing to a feather edge at the top. The flap is of lesser height than the bristles and at the top is preferably cut in the form of a number of short fingers 13 so as to increase its flexibility along the top. The flap being held in a concave position across its base, is kept in a relatively rigid

condition, without its desired flexibility at its outer end being impaired. Since it is desirable to have the conduit discharge into the cylinder 5 toward the top of the same, 5 said conduit cuts across the socket as shown and the base member 10 and the bottom of the flap are therefore recessed to avoid this portion of the conduit.

Especially made to cooperate with the 10 body is a collapsible tube 14 containing the cream etc. to be dispensed onto the brush. The body of the tube at the top is the same diameter as the bottom of the body so as to make a smooth junction therewith. The relatively small neck 15 is joined onto the body of the tube with a flaring portion 16 whose angularity is greater than that of the bore 3 of the body, so that the two bodies will only contact with each other around their 20 outer edges. The purpose of this arrangement is the same as set forth in the previously mentioned patent.

The neck is adapted to project into the bore 2 to abut against the top of the same and 25 thus communicate with the adjacent end of the conduit. Intermediate its ends the neck is provided with circumferentially spaced screw flanges 17 adapted to fit the bore and to pass by similar cooperating flanges 18 30 projecting inwardly from the bore. These flanges are arranged so that when the neck flanges have been projected past and above the bore flanges by a longitudinal movement between the body and tube, and the one is 35 then rotated relative to the other, the outer end of the neck will be brought into firm contact with the body at the bottom of the conduit.

Means to insure only a tube of the proper 40 cooperating nature being used with the brush is provided in the form of a groove 19 cut from top to bottom of one of the flanges 17, and a lug 20 projecting inwardly from the bore between the flanges 18. In this manner 45 a tube to be inserted and properly engaged with the body must have a flange-groove before its flanges can pass into position above those of the bore.

In case it is desired to use the brush with 50 out the tube and the self-feeding feature, I provide a handle member 21 of the same diameter as the tube and with a stem 22 the same size as the tube neck. This stem is provided with screw flanges 23 the same as the 55 tube flanges 17, so that said stem may be detachably connected to the body 1 in the same manner as the tube.

In operation to dispense cream from the tube, the trigger 7 is depressed to likewise 60 depress the plunger clear of the conduit outlet, while at the same time the tube is squeezed. The cream is thus exuded from the conduit past the plunger and onto the flap in the form of a small ribbon, to a length 65 determined by the user to be sufficient for

his purpose. During this operation the brush is preferably held so that the flap is horizontal and disposed below the plunger. When sufficient cream has been dispensed 70 the plunger is released and whatever cream remains in the cylinder between the conduit and the outer end of said cylinder will be also ejected onto the flap, and said cylinder will be cleaned and sealed against the admission of air to the adjacent end of 75 the conduit. The flap is then wiped against the face to transfer the cream thereto, which is then brought to a lather by applying the brush to the face in the usual manner. The flexibility and relative shortness of the flap 80 avoids any interference of the same with the movement of the bristles as the brush is worked over the face.

Only as much cream as is actually needed may thus be dispensed from the tube, and all 85 such cream may be easily and conveniently transferred to the face.

From the foregoing description it will readily be seen that I have produced such a device as substantially fulfills the objects 90 of the invention as set forth herein.

While this specification sets forth in detail the present and preferred construction of the device, still in practice such deviations from such detail may be resorted to as do 95 not form a departure from the spirit of the invention, as defined by the appended claims.

Having thus described my invention what I claim as new and useful and desire to secure by Letters Patent is:

1. A lather brush comprising a body member, bristles projecting upwardly from one end thereof, means on the other end of the body for connection to a cream holding tube, a cream dispensing conduit leading through 105 the body to provide communication between the tube and the exterior of the body at the same end as and to the outside of the bristles, and a substantially flat non-porous element mounted in connection with but separate 110 from the bristles and body between the bristles and outer end of the conduit and on which cream exuding from the conduit is initially received.

2. A structure as in claim 1, in which said 115 element is in the form of a flexible flap extending lengthwise of the bristles from the base of the same and of greater width than the conduit outlet.

3. A structure as in claim 1, in which said 120 element is in the form of a flexible flap extending lengthwise of the bristles from the base of the same and of greater width than the conduit outlet, the flap being tapered to be relatively thin at its outer end and being 125 bent at its base so as to have a concave curvature in a plane at right angles to the longitudinal axis of the body.

4. A lather brush comprising a body having 130 a socket in one end, a holder to remov-

ably fit in said socket, bristles mounted in said holder; a portion of the periphery of the socket and the corresponding periphery of the holder having a concave curvature relative to the exterior contour of the body and said curved portions being spaced apart, and a flexible flap removably wedged at its base end between the concave surfaces of the socket and holder and extending alongside the adjacent bristles.

5 5. A lather brush comprising a body, bristles projecting from one end of the same, and a flexible flap to initially receive cream mounted in connection with the body and bristles 10 to one side of the latter and projecting lengthwise of and against the adjacent ones of said bristles.

In testimony whereof I affix my signature.
